UNITED STATES PATENT OFFICE.

WILLIAM F. SERVICE, OF JERSEY CITY, NEW JERSEY, ASSIGNOR TO WILLIAM M. STERLING, OF MIFFLINBURG, PENNSYLVANIA.

SHOCK-ABSORBER.

1,172,315.

Specification of Letters Patent.

Patented Feb. 22, 1916.

Application filed January 29, 1913. Serial No. 744,802.

To all whom it may concern:

Be it known that I, WILLIAM F. SERVICE, a citizen of the United States, and a resident of Jersey City, county of Hudson, and State of New Jersey, have invented certain new and useful Improvements in Shock-Ab-sorbers, of which the following is a specifi-cation.

This invention relates to shock absorbers for automobiles of the type wherein the compression of air is utilized to check the excessive action of the springs when the vehicle encounters irregularities in the road bed.

15 The primary object of the invention is the devising of means whereby the shock that would otherwise occur from the compression of the vehicle springs is prevented by the compression of a volume of air, and 20 whereby the shock that would otherwise follow due to the recoil of the springs is prevented by a further compression of a part of the volume of air already compressed. The various other objects of the invention 25 will be more fully set forth in the following description of the invention which consists in the new and novel features of construction and combination of parts hereinafter set forth and claimed.

30 This invention consists of low and high pressure cylinders arranged to move in op-posite directions, and provided, each, with a piston which is operatively connected to the other cylinder to adapt the pistons to 35 operate alternately on their compression strokes, and means for permitting air to pass under a predetermined pressure from the low pressure to the high pressure cylinder on the compression stroke of the low 40 pressure cylinder to thereby supply air under pressure for the compression stroke of the high pressure cylinder.

Referring to the accompanying draw-ings:—Figure 1 is a central sectional eleva-tion of the shock absorber. Fig. 2 is a view simi-lar to Fig. 1 of the upper end of the absorber showing a modification, and Fig. 3 is a view similar to Fig. 2 showing an-other modification.

45 The low pressure cylinder of the device comprises a cylinder 1 provided with a closed head 2 at the outer end, and a piston 3 adapted to work in the cylinder.

50 The high pressure cylinder comprises the cylinder 4 secured at its inner end to the

piston 3 which acts as a head therefor, the cylinder 4 at the same time serving as a piston rod for the piston 3. The cylinder 1 is provided at its inner end with the open head 5 through which the cylinder 4 passes. A closed head 6 is secured to the outer end of cylinder 4, and is preferably extended to serve as a head for the cylinder 7 to which it is secured. This cylinder is not essential but is preferably used as a dust shield to prevent dust from entering the cylinder 1 through the openings in its head 5. The shield is provided with perforations to permit air to enter and is of suitable length to overlap the cylinder 1.

55 The high pressure cylinder is provided with a piston 8 secured to a rod 9 which extends into the cylinder 1 through an ori-fice in the piston 3 and is secured at its outer end in the head 2. A stuffing box 10 is here 75 shown in the piston 3 for the piston rod 9 and an orifice 11 is provided through the piston 3 to afford an uninterrupted com-munication between the active sides of the two cylinders. If desired, however, the ori-fice and stuffing box can be omitted and the 80 communication between the two cylinders can be provided for through the opening in the piston 3 through which the rod 9 passes.

70 The pistons are here shown as formed of cup shaped leather; the piston 8 being formed of the cup shaped disk of leather 12 directed toward the compression side of the cylinder and supported between the col-lars 13 and 14, and the piston 3 being 85 formed of the cup shaped disk 15 directed toward the compression side of the cylinder and supported between the collars 16 and 17. The collars 14 and 17 form a snug slid-ing fit with their respective cylinders, and 90 are each provided with peripheral slots 18 to permit air to pass them. The cup leather type of pistons are preferably used as they permit the leakage of air past them when they are at rest and also permit air to pass 95 to the compression end of the cylinders when they are moving from that end. The piston 3 is provided with an orifice 19, in which is arranged a ball valve 20, seated by a spring 21 to permit air to pass from 100 the cylinder 1 to the cylinder 4, the spring being of a suitable strength to permit the valve being opened only when the desired 105 pressure has been reached in the cylinder 1. The device is provided with suitable means, 110

as for instance, the perforated lugs 22, for securing it between the spring and chassis of the vehicle, or otherwise in the usual manner.

5 Figs. 2 and 3 are modifications of Fig. 1 in that the cylinder 4 of Fig. 1 is closed at its outer end, whereas in Fig. 2 it is provided with an opening controlled by the ball valve 23 to permit an exit of air, while 10 in Fig. 3 an opening is provided which is regulated by a cock 24.

The operation of the device is as follows:—When the running gear of the vehicle receives a jolt, the result is to 15 press the springs. This forces the ends 2 and 6 of the device toward each other thereby compressing the air in the low pressure cylinder 1. This prevents the shock that would occur from the excessive compression 20 of the springs. During this period when a predetermined pressure has been reached in the low pressure cylinder, the valve 20 opens and permits part of the compressed air to escape into the high pressure cylinder 4. When the recoil of the compressed vehicle springs begins the tendency 25 is to move the ends 2 and 6 of the device away from each other. This produces a compression of the already compressed air 30 in the high pressure cylinder 4 and thereby checks the shock to the chassis that would otherwise occur. The shock due to the recoil of the springs is much more noticeable than the shock due to their compression. 35 It is for this reason that the high pressure cylinder is used to prevent this shock and the low pressure cylinder to prevent the lesser shock due to the compression of the springs.

40 Immediately upon the checking of the recoil shock, the pressure in the high pressure cylinder begins to be released by the air therein leaking through the orifice 11 to the low pressure cylinder, whose volume has 45 been increasing during the compression in the high pressure cylinder with a corresponding decrease in its pressure, thereby admirably adapting it for releasing the pressure in the high pressure cylinder. By thus 50 releasing the pressure in the high pressure cylinder, the springs are permitted to gradually assume their normal positions.

The cup shaped leather parts of the pistons 3 and 8 permit leakage of air past them 55 when they are not compressing, thereby permitting the pressures in the cylinders to equalize to atmosphere. In Fig. 1 the movement of the piston 8 toward the head 6 compresses the air in the outer end of the cylinder 4, thereby assisting the low pressure cylinder 1 in absorbing the shock of compression of the springs, and at the same time permitting part of the air thus compressed to pass it and enter the inner end 65 of the cylinder 4, thereby adding to the

effectiveness of the high pressure cylinder on the recoil of the springs.

In Fig. 2 the valve 23 permits the air in the outer end of the cylinder 4 to escape and thereby to a greater or less extent, prevents the compression in that end of the cylinder during the compression in the low pressure cylinder, and causes a partial vacuum to be formed during the compression in the high pressure cylinder. 75

In Fig. 3 the cock 24 permits the outer end of the cylinder 4 to be more or less neutral depending upon the size of the opening afforded by the cock.

While I have shown a preferred embodiment of my invention, it is obvious that various changes within the skill of the mechanic may be made therein without departing from the spirit of the invention, provided the means set forth in the following claims be employed. 80

I claim—

1. A pneumatic shock absorber comprising a low pressure cylinder, a high pressure cylinder telescoped in said low pressure cylinder, a piston for the low pressure cylinder between said cylinders and operatively connected to the high pressure cylinder, and a piston for the high pressure cylinder operatively connected to the low pressure cylinder whereby one cylinder expands while the other compresses as the cylinders are moved axially relative to each other, said cylinders being in communication at their inner and compression ends. 100

2. A shock absorber comprising a low pressure cylinder, a high pressure cylinder, a piston for the low pressure cylinder between the said cylinders and operatively connected to the high pressure cylinder for compressing air in the outer end of the low pressure cylinder, and a piston for the high pressure cylinder operatively connected to the low pressure cylinder for compressing air in the inner end of the high pressure cylinder, said pistons being adapted to compress alternately, said cylinders being in communication at their compression ends to permit air being compressed in the low pressure cylinder to be forced in the high pressure cylinder previous to its compression stroke. 110

3. A shock absorber comprising a low pressure cylinder, a high pressure cylinder, a piston for the low pressure cylinder operatively connected to the high pressure cylinder for compressing air in the outer end of the low pressure cylinder, a piston for the high pressure cylinder operatively connected to the low pressure cylinder for compressing air in the inner end of the high pressure cylinder, said pistons being adapted to compress alternately, and means for permitting air to pass from the low pressure cylinder to the high pressure cylinder. 125

der when a predetermined pressure has been attained in the low pressure cylinder at the compression stroke thereof.

4. A shock absorber comprising a low pressure cylinder, a piston for the low pressure cylinder, a high pressure cylinder secured to the said piston to serve as a piston rod therefor, said piston extending between the two cylinders, a piston for the high pressure cylinder, and a piston rod for the piston of the high pressure cylinder passing through the active end of the high pressure cylinder operatively connected to the low pressure cylinder, said cylinders being in communication at their compression ends. 55

5. A shock absorber comprising a low pressure cylinder, a piston having sliding engagement with the inner wall of the low pressure cylinder, a high pressure cylinder spaced from the low pressure cylinder and secured to the said piston to serve as a piston rod therefor, a piston for the high pressure cylinder, and a piston rod for the piston of the high pressure cylinder passing through the active end of the high pressure cylinder operatively connected to the low pressure cylinder, said cylinders being in communication at their compression ends, one of said pistons being adapted to permit air to pass it when at rest and when moving away from the compression end of its cylinder. 70

6. A shock absorber comprising a low pressure cylinder, a high pressure cylinder, a piston for the low pressure cylinder operatively connected to the high pressure cylinder, a piston for the high pressure cylinder operatively connected to the low pressure cylinder, said cylinders having a permanent communication between their compression ends, and means for affording additional communication between the cylinders at their compression ends during the compression stroke of the low compression piston after a predetermined pressure has been reached. 85

7. A shock absorber comprising a low pressure cylinder, a piston having sliding engagement with the inner wall of the low pressure cylinder, a double acting cylinder 90

spaced from the low pressure cylinder and secured to the said piston to serve as a piston rod therefor, and adapted to serve as a high pressure cylinder at one end, and a low pressure cylinder at the other end, a double acting piston for the said double acting cylinder, a piston rod for the piston operatively connected to the low pressure cylinder and means for permitting air to pass from the low to the high pressure end of the double acting cylinder on the compression stroke of the low pressure cylinder, said double acting piston being adapted to operate on the high pressure end alternatingly with the operation of the low pressure cylinder and to operate on the low pressure end with the operation of the low pressure cylinder, said piston being adapted to permit air to pass it from the low pressure to the high pressure side on the lower compression stroke. 65

8. A shock absorber comprising an inner cylinder and an outer cylinder spaced from each other, a piston movable in the space between the said cylinders, a piston movable in the inner cylinder, said piston being rigidly connected to the outer cylinder, means permitting air under pressure to pass from the outer cylinder to the inner cylinder, and means for gradually equalizing the pressures on opposite sides of the piston in the inner cylinder when said piston is at rest. 75

9. A shock absorber comprising a two-stage air compressor and having a high pressure cylinder and a low pressure cylinder one within the other, a low pressure piston mounted on the high pressure cylinder and contacting with the inner wall of the low pressure cylinder, a high pressure piston mounted on the low pressure cylinder and contacting with the inner wall of the high pressure cylinder, and sealed on its compression stroke, said cylinders being in communication at their compression strokes. 80
